US00D738444S

(12) **United States Design Patent**
Hilson

(10) **Patent No.:** **US D738,444 S**
(45) **Date of Patent:** **** Sep. 8, 2015**

(54) **RESISTANCE TRAINER**

(71) Applicant: **Escape Fitness Limited**, Peterborough, Cambridgeshire (GB)

(72) Inventor: **Nicholas Hilson**, Peterborough (GB)

(73) Assignee: **Escape Fitness Limited**, Peterborough, Cambridgeshire (GB)

(**) Term: **14 Years**

(21) Appl. No.: **29/519,736**

(22) Filed: **Mar. 6, 2015**

(30) **Foreign Application Priority Data**

Sep. 10, 2014 (EM) 002535195-0001

(57) **CLAIM**

The ornamental designs for the resistance trainer, as shown and described.

DESCRIPTION

FIG. 1 is an isometric view of the resistance trainer of the present invention;

FIG. 2 is a top view of the resistance trainer of FIG. 1;

FIG. 3 is a bottom view of the resistance trainer of FIG. 1;

FIG. 4 is a side view of the resistance trainer of FIG. 1;

FIG. 5 is the other side view of the resistance trainer of FIG. 1;

FIG. 6 is a front view of the resistance trainer of FIG. 1;

FIG. 7 is a back view of the resistance trainer of FIG. 1;

FIG. 8 is an isometric view of a second embodiment of the resistance trainer of the present invention;

FIG. 9 is a top view of the resistance trainer of FIG. 8;

FIG. 10 is a bottom view of the resistance trainer of FIG. 8;

FIG. 11 is a side view of the resistance trainer of FIG. 8;

FIG. 12 is the other side view of the resistance trainer of FIG. 8;

FIG. 13 is a front view of the resistance trainer of FIG. 8; and,

FIG. 14 is a back view of the resistance trainer of FIG. 8.
